UNITED STATES PATENT OFFICE.

HENRY W. STAPLES, OF NEW HAVEN, CONNECTICUT, ASSIGNOR TO WINCHESTER RE-
PEATING ARMS COMPANY, OF NEW HAVEN, CONNECTICUT, A CORPORATION OF
CONNECTICUT.

BATTERY HAND LAMP.

Application filed July 26, 1927. Serial No. 208,455.

This invention relates to battery hand lamps of the type including a casing for the battery, a lamp bulb, a switch mechanism for controlling the electric current through the battery and the bulb, and a bottom end cap for closing the bottom end of the casing and holding the battery in proper position within the casing. The present invention more particularly concerns supporting means carried by the bottom end cap of a hand lamp of the type described, whereby such lamp may be conveniently supported from a hook, peg or other support.

It has been found desirable and convenient to provide hand lamps of the type described with suitable means, such as a loop or ring, for use in hanging the lamp vertically from a hook or peg, the lamp casing extending downwardly from such support. A supporting means of this type should be so designed and mounted that it may be folded down and retained out of the way while the lamp is being carried in the hand, while at the same time being readily accessible for use when it is desired to hang the lamp from a support. The supporting means should be simple and inexpensive and should be readily applicable to hand lamps of the conventional type.

With the above and other considerations in mind, it is proposed in accordance with the present invention to provide a battery hand lamp having an improved form of supporting means mounted on the bottom end cap thereof, and, more specifically, it is proposed to provide a supporting ring or loop of this type which is so mounted and arranged that it may be folded down outside of the end cap and releasably retained in its retracted position.

It is a further object of the present invention to provide a supporting means of the type described which is so located with respect to the hand lamp casing that the lamp may be hung in a vertical position from a hook, peg or other supporting projection on a plane vertical surface.

It is a still further object of the present invention to provide a lamp supporting means of the type described which is simple in construction, inexpensive to manufacture, and readily applicable to hand lamps of the conventional type without substantial changes in the design of such lamps.

Other objects, advantages and characteristic features of the invention will become apparent as the description thereof progresses.

In describing the invention in detail, reference will be made to the accompanying drawing, in which;

Figure 1 is a sectional side view of a portion of the casing of a hand lamp, together with a bottom end cap embodying the supporting means of the present invention;

Fig. 2 is a view of the lower end of the bottom end cap of Fig. 1, showing the lamp supporting means;

Fig. 3 is a side view of the end cap and supporting means of Figs. 1 and 2;

Fig. 4 is a side view of a hand lamp end cap embodying a modified form of the supporting means of the present invention;

Fig. 5 is a sectional side view of a second modified form of the lamp supporting means of the present invention;

Fig. 6 is a view of the lower end of the end cap and supporting means shown in Fig. 5; and

Fig. 7 is a side view of the form of the invention shown in Fig. 1, showing the lamp supporting means open and in use.

Referring first to the modification of the invention shown in Fig. 1, the lamp comprises a cylindrical battery casing 1, which may be formed of sheet metal or other suitable material, carrying a battery 2 composed of one or more dry cells arranged end to end in series connection in the usual manner. A cylindrical bottom end cap 3 closes the lower end of the battery casing 1, being secured thereto by a screw threaded engagement therewith as shown. The electrical circuit between the casing 1 and the battery 2 is preferably completed through a spiral coil spring 4 which is sprung or otherwise suitably secured within the end cap 3. The end cap shown in Fig. 1 is of the type which is provided with an inwardly extending circular ledge 5 which forms a stop to engage the lower edge 6 of the casing 1, and so to limit the position of the cap 3 when it is screwed on to the casing 1. The ledge 5 is usually formed by turning or pressing an inwardly extending circular groove or depression 7 into the outer surface of the cap 3.

Referring now more particularly to the form of the supporting means of the present

invention, this means comprises an arcuate loop 8, preferably formed of heavy spring steel wire, which loop is hingedly secured to the end cap 3 by its inturned aligned ends 9 and 10 which extend respectively into aligned openings 11 and 12 in the side wall of the cap 3 near the bottom end thereof as clearly shown in the drawings. The loop 8 has a larger radius of curvature than the outside radius 10 of the cylindrical wall of the end cap 3, and is mounted to lie substantially concentric to this cylindrical wall when folded down over the end cap as shown in Figs. 1, 2 and 3. The aligned openings 11 and 12 are both disposed 15 to one side of a diameter of the end cap, so that the axis about which the loop 8 swings is spaced from the center of the cap, as clearly shown in Figs. 2 and 7. This arrangement brings the supporting loop near to one side 20 of the hand lamp when the loop is swung at right angles to the end of the cap 3, thereby permitting the lamp to hang flat against a vertical wall or surface 13 when the loop 8 is passed over a fixed support 14 extending 25 from such surface, as shown in Fig. 7.

The supporting loop 8 of the modification shown in Fig. 1 is of such a size that it may be sprung into the groove 7 formed by the stop ledge 5 of the end cap, and may thereby be 30 held in place when not in use. When the loop 8 is folded down over the end of the cap 3, it engages the cylindrical wall of the cap at the point 15, and upon being forced toward the groove 7, expands enough to snap over the 35 lower edge of this groove and is then releasably retained therein. When it is desired to hang the lamp from a support, the loop is pressed downward, whereupon it expands slightly, passes over the lower edge of the groove 7 and then contracts against the cylindrical wall of the cap 3. The contracting of 40 the resilient loop 8 against the wall of the cap 3 after being pressed out of the groove 7, causes the loop to be sprung or snapped to a 45 position substantially at right angles to the end of the cap where it is ready for use. It is evident that by the means described, the loop 8 is releasably retained in its closed position 50 by engagement in the groove which forms a stop ledge within the end cap.

In case no stop ledge 5 and corresponding external groove 7 are provided upon the end cap, the loop 8 may be retained in its retracted position by engagement within one of the 55 grooves formed on the end cap by the screw threads employed to secure the end cap to the casing. A cap 16 of this type has been shown in Fig. 4, the loop 8 being hinged to this cap in the manner as that described above 60 in connection with Fig. 1. When folded down over the end cap, the loop 8 of Fig. 4 engages and is snapped over one or more of the ledges or extensions formed by the screw threads 17 on the cap, and is releasably retained between two of these ledges.

In the modification shown in Figs. 5 and 6, an outwardly extending lug 18 is pressed from or otherwise suitably formed on the cylindrical wall of the end cap 19, and the supporting loop 8 is snapped over this lug and 70 retained in its retracted position thereby in a manner which is evident from the drawings. The lug 18 may be employed where other extensions or depressions which may be used as 75 loop retaining means are not previously formed on the end cap for other purposes, or where for any reason such extensions or depressions cannot be conveniently employed for this purpose.

The hand lamp supporting means described 80 is very simple and effective and embodies several advantageous features. In the modifications shown in Figs. 1 through 4 and 7, the supporting loop is retained in its retracted position by means which are usually formed 85 on hand lamp end caps for other purposes and for this reason the supporting loop may be applied to the end cap by merely forming aligned openings therein and without changing the design of the cap. The location of 90 the axis of the hinge connection between the supporting loop and the end cap to one side of the center of the cap enables the hand lamp to be hung from a fixed support against a vertical surface without tilting and extending outwardly from such surface. Further, the loop is so arranged and disposed that it 95 may be quickly and easily sprung to its open or its retracted positions by the operator.

Although the hand lamp supporting means 100 of the present invention has been described in connection with certain specific embodiments, it should be understood that certain changes in the form and arrangement of the elements may be made without departing 105 from the scope of the invention as defined by the appended claims.

I claim:

1. In a hand lamp, the combination of a battery casing, a cylindrical end cap secured 110 to one end of said casing, a substantially arcuate supporting loop having a larger radius of curvature than the outside radius of said end cap hingedly secured to the cylindrical wall of said cap adjacent the end thereof and movable to a position substantially concentric with the outside cylindrical wall of said cap, and a projection on the cylindrical wall of said cap for engaging said loop and releasably retaining said loop in a 115 position substantially concentric with said cylindrical wall.

2. In a hand lamp, the combination of a tubular battery casing, an end cap secured 120 to one end of said casing, a supporting loop hingedly secured to said end cap and movable to a retracted position substantially surrounding said cap, and a single means on said end cap for use in securing said cap to said casing and for releasably retaining 125

said supporting loop in its retracted position.

3. In a hand lamp, the combination of a tubular battery casing, a cylindrical end cap secured to one end of said casing, a substantially arcuate supporting loop hingedly secured to the cylindrical wall of said end cap and movable to a retracted position substantially concentric with the cylindrical wall of 10 said cap and a single means on the cylindrical wall of said end cap for use in securing said end cap to said casing and for releasably retaining said supporting loop in its retracted position.

15 4. In a hand lamp, the combination of a tubular battery casing, a cylindrical end cap screw threadedly secured to one end of said casing, a resilient substantially arcuate supporting loop hingedly secured to said cap and 20 movable to a retracted position substantially concentric with said cap, and means on the cylindrical wall of said cap for limiting the extent to which the said cap may be screwed on to said casing and for releasably retaining 25 said supporting loop in its retracted position.

5. In a hand lamp, the combination of a tubular battery casing, a cylindrical end cap secured over one end of said casing, and a 30 resilient supporting loop having inturned aligned ends journalled in openings in the cylindrical wall of said cap and movable to a retracted position substantially surrounding said cylindrical wall of said cap, the 35 cylindrical wall of said cap having a groove therein forming a stop ledge within said cap for limiting the position of said cap on said casing, and the edge of said groove releasably retaining said supporting loop in its retract- 40 ed position.

6. In a hand lamp, a battery casing, a cylindrical end cap secured to one end of said casing, a substantially arcuate supporting loop hingedly secured to one end of said cap 45 along an axis spaced from the central axis of said cap, said supporting loop having a larger radius of curvature than the outside radius of the cylindrical wall of said cap

and being movable to a retracted position substantially concentric with the cylindrical 50 wall of said cap, and means on the cylindrical wall of said cap for releasably retaining said supporting loop in its retracted position.

7. In a hand lamp, a battery casing, a cylindrical end cap secured to one end of said casing, an arcuate supporting loop hingedly secured to said end cap along an axis extending transversely of said cap and spaced from the center of said cap and from a plane parallel to said axis and tangent to the cylindrical 60 wall of said cap, said supporting loop being movable to a retracted position around the cylindrical wall of said cap, and means for releasably retaining said loop in its re- 65 tracted position.

8. In a hand lamp, a battery casing, an end cap removably secured to one end of said casing, a supporting loop hingedly secured to said end cap and movable to a retracted po- 70 sition around the outside of said cap, and means on said cap for simultaneously fixing the position of said cap relative to said casing and releasably retaining said supporting 75 loop in its retracted position.

9. In a hand lamp, the combination of a battery casing having an opening therein, a cap removably secured to said casing over said opening, a supporting loop hingedly secured to said cap and movable to a retracted 80 position adjacent said cap, and a single means on said cap for use in securing said cap to said casing and for releasably retaining said supporting loop in its retracted position.

10. In a hand lamp, a battery casing, an end cap secured to said casing, a supporting 85 loop hingedly secured to one end of said cap along an axis spaced from the center of said cap, said supporting loop being larger than the outside dimensions of said cap and being 90 movable to a retracted position substantially surrounding the outside of said cap, and means on said cap for releasably retaining said supporting loop in its retracted position.

In testimony whereof I affix my signature.
HENRY W. STAPLES.
